UNITED STATES PATENT OFFICE.

FRANK M. JOSLIN, OF AMSTERDAM, NEW YORK, ASSIGNOR TO INMAN MANUFACTURING COMPANY, INC., OF AMSTERDAM, NEW YORK, A CORPORATION OF NEW YORK.

COLLAPSIBLE CARTON.

1,384,069.

Specification of Letters Patent. Patented July 12, 1921.

Application filed May 15, 1916. Serial No. 97,577.

To all whom it may concern:

Be it known that I, FRANK M. JOSLIN, a citizen of the United States, residing at Amsterdam, Montgomery county, State of New York, have invented certain new and useful Improvements in Collapsible Cartons, of which the following is a specification.

The invention relates to collapsible cartons, and more especially to such cartons adapted to be used as an egg case.

The objects of the invention are to make such a device so that it will be strong, durable, and easily collapsed; to provide a top closure; and to provide self-contained means for locking the closure shut.

These and other features of the invention including certain details of construction and combination of parts will be set forth in the following description and pointed out in the claims.

Figure 1 is a perspective view of the carton;

Fig. 2 is a cross section through the carton;

Fig. 3 is a view of the blank, which forms the partition, the bottom, two extra sides and the top closure.

The carton comprises the usual longitudinal side walls 10, the transverse side walls 11, the transverse partitions 12, and a longitudinally extending partition 13. These parts are interconnected in any suitable manner to form cells. As shown at 14, the longitudinally extending members are slotted at spaced intervals at their upper edges, and have apertures 15 alined with the slits. The transverse members have spaced irregular slits 16 formed so as to produce a hook 17, and this hook is adapted to catch in an aperture 15. Thus the side walls and partitions may be securely interconnected and locked in position.

As shown in the drawings, a single blank is cut and bent to form a partition, the bottom two side walls and the top closure. This blank is clearly illustrated by Fig. 3. The blank is cut out to form two sections 18, 19 joined together by the two tabs 20. Obviously, two blanks 18, 19 might be used instead of a single blank. However, I prefer a single blank as a tab is thus formed the two parts of which are held together and cannot spread apart when the slot 22 is put over the same.

The section 18 is folded or bent so as to

form part of the longitudinally extending partition 13, half of the bottom, an extra side and a part of the top closure. The other section 19 of similar size and shape forms with the section 18 the partition 13, 60 also the other half of the bottom, a second additional side on the opposite side from the first, and the remaining part of the top closure. Thus the longitudinal partition 13 is formed from part of each of the two sections 18 and 19. These sections at the edges which form the upper edge of the partition are provided with two tabs 20, each of which is formed with a slot 21. One of the sections as 19 is made with slots 22 adjacent the edge 65 70 opposite the tabs 20. These slots 22 are located so as to take over the tabs 20, when the section is in position to form its part of the top closure.

The corresponding edge of the section 18 75 is formed with two tongues 23 which are of such dimensions and so located that they will project through the slots 21 when the top closure is in closed position. On each side of each of the tongues alined slots 24 80 are formed, each pair of which is adapted to act like the slots 21 and take over a tab 20.

It will be seen that the sections 18, 19 thus together form a top closure and also self-contained means to lock the closure in 85 closed position. This may be done in more than one way. The section 18 may be placed with the slots 24 taking over the tabs 20, then the slots 22 of section 19 are passed over the said tabs, and finally the tongues 23 90 are each passed through a slot 21 in a tab. Thus the top closure is locked in closed position. The top may also be closed by first moving the section 19 to place apertures 22 over the tabs, and then operating section 18 95 to place slots 24 over a tab and finally sticking each of the tongues 23 through one of the slots 21.

It is obvious that the carton may be easily assembled, that is, the parts may be put 100 together without any difficulty, or an assembled carton may be collapsed so as to occupy a minimum of space.

It will be noted that the double partition strengthens the device, as does the additional side walls. These side walls also protect the contents of the carton and provide a cushion to some extent, as the said additional side walls are spaced from the side walls 10. By having the locking means 110

self-contained in the single blank, a very positive lock is provided and the stresses induced thereby are localized in the said blank. Furthermore, the arrangement is 5 such that the parts can be manufactured very cheaply.

While a carton having two tabs 20 and corresponding tongues has been described, it is obvious that the number of tabs and 10 tongues used will depend on the size of the carton or box, and any number desired may be used. Furthermore, although a carton having twelve cells has been illustrated, the number of cells is not material, as the invention is applicable to cartons having two 15 or more cells.

Having thus described the invention, what is claimed and desired to be secured by Letters Patent is:

- 20 1. A collapsible carton or box having front and rear side walls, a partition parallel to said walls, a top closure, a bottom, two additional side walls outside of the first mentioned walls, the said bottom, additional 25 side walls, partition and top closure being formed from a single blank, and co-operating means on the partition and closure to lock the latter in closed position.
2. A collapsible carton or box, having a 30 top closure formed with a slot and a tongue; and a partition having a tab extending through the slot, said tab formed with a slot to receive the tongue.

3. A collapsible carton or box having a top closure consisting of two overlapping parts, one part formed with a slot and the other a tongue, a partition having a tab adapted to extend through said slot and said tab having a slot adapted to receive said tongue. 35

4. As an article of manufacture, a blank comprising two substantially equal sized sections connected by a tab formed with two spaced slots, one section at the edge opposite the said tab having a tongue adapted 40 to enter said slots, the other section adjacent the edge opposite the said tab formed with a slot adapted to receive the tab. 45

5. A collapsible carton or box having a partition, bottom, side walls and top formed 50 from a single blank, a tab on said partition and a tongue on the top interlocking with said tab to secure the top in closed position.

6. A collapsible carton or box having a top consisting of two sections each hinged 55 to the top of a side wall, a partition having a tab formed with a slot, the top sections having registering slots adapted to receive the tab and one section having a tongue adapted to extend through the slot in the 60 tab.

In testimony whereof I affix my signature.
FRANK M. JOSSLIN.
